UNITED STATES PATENT OFFICE

2,054,607

ROTARY OIL BURNER

Theophilus H. Smoot, Baltimore, Md., assignor to Anchor Post Fence Company, Baltimore, Md., a corporation of Maryland

Application April 25, 1934, Serial No. 722,381

10 Claims. (Cl. 158—77)

The present invention relates to rotary oil burners which are particularly useful for employment in connection with heaters for houses, apartments, or institutional use, and which heaters are of the type that ordinarily burn coal and rely on natural stack draft or chimney suction for drawing air into the heaters and for conducting away the products of combustion. The rotary oil burner is also adapted to be applied to boilers 5 of a type designed especially for use in connection with oil burners, and the rotary oil burner of the present invention may be used on boilers originally designed for burners other than that of the present invention as well as boilers especially constructed for the rotary oil burner of the present invention.

At the present time, one mode of creating heat by burning oil within the firebox or combustion chamber of such a heater and the supplying of 20 the heat thus created to certain parts of the heater and particularly to those parts which provide the wall of the firebox or combustion chamber, is dependent upon the functioning of a rotary burner head that centrifugally and horizontally 25 projects the oil in atomized form over and into the upper portion of an air stream or strata maintained by a fan of the rotary head which causes the air to continuously move outwardly over and across a horizontally extending hearth defining 30 the floor of the firebox or combustion chamber and relative to which hearth the burner head is generally centrally located.

A rotating burner head such as just referred to generally comprises an atomizing fuel element 35 and an air fan both carried by and secured to the upper end of a motor shaft which is provided by a vertically extending shaft of the rotor of an electric motor that is carried by the main frame of the burner.

40 The burner forming the subject matter of the present invention is designed for use in connection with hearth constructions of various types, but is particularly useful in connection with hearths having the arrangement and novel features of 45 construction shown and described in my copending application filed May 17, 1934, Serial No. 726,139.

In some of the rotary oil burners as heretofore 50 constructed attempts have been made to regulate the air flow from the fan by controlling the inflow of air to the fan. This, however, has certain objectionable characteristics, and one of the objects of the present invention is to provide a construction for enabling the flow of air from the 55 fan to be regulated by means of a vertically ad-

justable air gate which cooperates with the main frame of the burner and with the delivery portion of the fan whereby the flow of air from the fan is directly dependent upon the vertical position of the air gate.

It is also an object of the invention to permit 5 a micrometer adjustment of the air gate so that by allowing only just the right amount of air to enter the combustion chamber wasteful recirculation will be rendered impossible.

In rotary oil burners it is advisable to employ 10 a standard main frame, a motor and burner heads of different sizes, and an object of the present invention is to provide a construction whereby this 15 can be accomplished so that if during the life of the burner the boiler or furnace should have to be replaced by a larger one a new head assembly 20 may be supplied to fit the new boiler or furnace at a trifling expense.

It is also an object of the invention to provide 25 an oil atomizer constructed so that it is in effect air cooled by the functioning of the air fan with which it is associated and also so arranged in respect to the air fan that it is in effect sealed thereby and in fact, a construction that is such 30 that substantially the entire atomizer is surrounded by air as the air flows through the fan so that the atomizer will be protected from direct heat of the furnace by the air fan structure which will in effect serve as a seal for the atomizer.

Another object of the invention is to protect 35 from the direct heat of the furnace the nut or other fastening means for securing the fan and the atomizer to the vertical shaft of the motor, by arranging the nut in a depression in the fan. This will in effect prevent the direct heat of the 40 furnace from being conducted through the rotor shaft to the motor.

It is also an object of the invention to provide 45 a burner construction which will permit the motor thereof to be readily removed, or any other part of the burner to be removed or changed as, for example, to supply an oil atomizer, an air fan or an air gate adapter of different size with a minimum amount of labor and at a low cost.

With these and other objects in view, the invention consists in the novel construction, combination and arrangement of parts hereinafter 50 fully described, illustrated in the accompanying drawings, and pointed out in the claims hereto appended, it being understood that various changes in the form, proportion, and minor details of construction, within the scope of the 55 claims, may be resorted to without departing

from the spirit or sacrificing any of the advantages of the invention.

In the drawings:—

Fig. 1 is a vertical sectional view of a rotary oil burner constructed in accordance with this invention, the motor being in elevation and the section being taken on the line 4—4 of Fig. 5.

Fig. 2 is an elevation of the rotary oil burner partly in section to illustrate the arrangement 10 of the oil tubes.

Fig. 3 is a vertical sectional view on the line 3—3 of Fig. 6.

Fig. 4 is a vertical sectional view somewhat diagrammatic of a portion of a furnace illustrating 15 a manner in which the rotary burner may be installed and used in conjunction with the heater of the type ordinarily used in homes, apartment houses and institutions.

Fig. 5 is a plan view of the rotary oil burner.

Fig. 6 is a horizontal sectional view on the line 6—6 of Fig. 1.

In the accompanying drawings in which is illustrated the preferred embodiment of the invention 1 designates a burner main frame supported by legs 2 which provide a three point support, whereby when the rotary burner rests upon a firm foundation the main frame will be firmly supported so that it will not tilt or rock. Each leg comprises telescoping sections having 30 an upper tubular section 3 which is connected to a portion of the main frame 1 by having the upper end 4 threaded and screwed into a threaded socket 5 of a depending boss 6 of the main frame 1. The central portions of the three legs 35 are connected by a C-shaped bracing yoke 7 having leg receiving bosses 8 provided with openings spaced substantially 120 degrees from each other, as clearly illustrated in Fig. 6 of the drawings. Because of the yoke being C-shaped, there is provided 40 a construction whereby an electric motor 9 may be removed by lateral movement through the open portion of the C-shaped yoke. The opening of each boss 8 of the yoke receives the lower exteriorly threaded end 10 of the upper tubular section 3 and is positively clamped in place between upper and lower locking nuts 11 and 12, the latter of which is interiorly threaded at 13 and 14. The upper nut 11 and the threaded portion 13 of the lower nut 12 firmly engage and 50 clamp the boss 8 between them. The interiorly threaded portion 14 of the nut 12 receives a lower leg member 15 which is exteriorly threaded so as to screw into the interiorly threaded portion 14 of the lower nut 12.

The lower end of the lower leg member 15 may be provided with a tip of rubber or other suitable material. Because of the locking effect resulting from the clamping action of the upper lock nut 11 functioning through the boss 8 to 60 and upon the upper end of the lower lock nut 12, the latter in effect becomes a locked-on part of the upper tubular section 3. A lock nut 16 which is arranged on the lower leg member 15 serves to lock the latter in place on the upper tubular section 3.

The several main parts of the burner are constructed of metal and when the C-shaped yoke 7 is clamped in place on the several leg members 70 there is provided a relatively strong rigid and stable construction whereby the burner thereof, as a whole, will remain properly positioned when once in place. Also by virtue of the adjustable leg structure, the rotary head of the burner can 75 be properly positioned as to vertical height and

also as to level or inclination according to the hearth upon which the burner is used.

The main frame which is substantially cylindrical is provided at the bottom with an inwardly extending integral horizontal plate 17 and 5 it also has an upper outwardly extending integral horizontal plate 18 located at an intermediate point between the top and bottom of the body portion of the main frame. The upper portion of the main frame extends above the upper horizontal flange and forms a cylindrical upwardly extending throat portion 19 which forms a guide for a vertically movable cylindrical air gate 20.

From the main frame plate 17 is supported or carried from the underside thereof an electric 15 motor 9 which may be held in place in any suitable manner, preferably by bolts 22 extending through bolt receiving openings 23 of lugs 24 and engaging threaded openings or sockets 25 in the bottom of the main frame, as clearly illustrated in Fig. 1 of the drawings. The rotor of the motor has a vertical shaft 25* that extends upwardly from the motor and carries at its upper end a burner head 26 comprising a rotary oil atomizer 27 and a rotary fan 28. The rotary 20 atomizer 27 which constitutes an oil atomizing and delivering member comprises an inverted cup-shaped body and oil ducts or tubes 29 leading from the inverted cup-shaped body of the atomizer. 30

The cup-shaped body portion which is open at the bottom forms an upwardly and outwardly extending peripheral wall 30 and a horizontal top wall 27'. From the lower end of the peripheral wall 30 and integral therewith there extends 35 an upwardly and inwardly inclined portion that forms a lip or flange 31. The lip or flange 31 diverges from the peripheral wall 30 and forms an annular oil receiving groove or gutter 32 at the lower interior portion of the cup. The horizontal top of the cup-shaped body portion extends from the upper portion of the peripheral wall inwardly to the vertical shaft and is provided with a central shaft receiving opening 33. The upper terminal portion 34 of the shaft is 40 reduced and threaded and the reduction of the shaft forms a shoulder 35 upon which the inverted cup-shaped body portion of the atomizer is seated.

The rotary fan 28 has a body portion 50 consisting of a disk having a substantially horizontal annular peripheral portion and a centrally depressed, tapered, approximately inverted, conical portion 36. The fan is provided at its periphery with an annular series of depending 55 vertical fan blades 37 located above the plane of the upper edge of the cylindrical body portion of the main frame, as clearly illustrated in Fig. 3 of the drawings. The oil ducts or tubes while being shown extending between the fan blades 60 may be arranged in any other desired manner and while the disk which forms the body portion of the fan may have the centrally depressed tapering portion such feature may, of course, be omitted, if desired. 65

The fan blades 37 are substantially rectangular and may vary in dimensions with the diameter of the fan. The centrally depressed body portion of the fan is provided with a shaft receiving opening 38 through which extends the 70 reduced threaded upper terminal portion 34 of the vertical motor shaft. The fan 28 is clamped in place on the shaft by a nut 39 which serves to secure the said fan 28 and through it the oil atomizer 27 in place on the shouldered end of 75

the vertical shaft 25. It will be noted that the depth of the depression 38 of the fan is sufficient for the nut to be practically protected against the direct effect of flames and products of combustion which at times tend to recirculate over the burner.

The cylindrical body of the burner frame is provided in its lower portion with an annular series of air inlet openings 40 and the throat portion 19 of the burner body has its upper edge spaced from the horizontal peripheral portion of the fan body and the fan blades 37 are located at the said space, as clearly illustrated in Figs. 1 to 3 of the drawings. The effective portion of the 15 said space between the upper edge of the burner body and the peripheral portion of the fan is controlled and adjusted by means of the vertically adjustable air gate 28 which is cylindrical and slidably mounted at the inner face of the 20 upper throat portion 19 of the burner frame.

The vertically adjustable air gate is slidably mounted on pins 41 carried by the throat portion of the burner frame at the inner face thereof and extending into the inclined slots 42 formed in the air gate. The inclined slots and the pins are arranged at intervals and when the cylindrical air gate is partially rotated by the means hereinafter described it is adjusted vertically for varying the effective size of the space 30 between the burner frame and the periphery of the fan. The vertically adjustable air gate is located beyond the vertical planes of and contiguous to the outer ends of the fan blades and it is adapted to cover the fan blades to a greater or 35 less degree according to its adjustment.

The rotary or angular movement is imparted to the air gate by means of a yoke construction comprising ears 43 rigid with and depending from the gate member at opposite sides thereof 40 and pivotally connected to the arms or sides of a yoke 44 which is curved to conform to the configuration of the burner frame. The yoke is provided with a centrally arranged arm forming a handle extension 45 which extends outwardly 45 through one of the air inlet openings 40. The outer portion of the handle is arranged between spaced ears 46 depending from the upper horizontal flange 18 and having threaded openings 47 for the reception of horizontal adjusting screws 48 located at opposite sides of the handle 50 of the operating yoke of the adjustable air gate and adapted to form a micrometer adjustment for the air gate.

The inner ends of the horizontal adjusting screws are arranged to abut against the side faces of the handle extension of the yoke and are adapted to clamp the same for holding the air gate at the desired adjustment. By adjusting the screws 48 any vertical adjustment of the air 55 gate within its range of movement may be made and after adjustment the air gate will be positively retained in its adjusted position. The pivotal connection between the ears 43 and the ends of the yoke plus the vertical yieldability of the 60 yoke permits vertical movement of the air gate without affecting the adjustment of the operating arm by the stop or adjusting screws 48. The ears 46 are preferably connected at their lower ends by a horizontal connecting portion 49 65 to provide a guide frame for the handle portion of the lever, but any other equivalent means may, of course, be employed for adjusting the operating yoke and for securing the same and the air gate in their adjustment. The screws 70 75 constitute stop members which may have their

inner ends positioned at various points between the spaced ears 46 and the threads of the screws provide a fine adjustment for the yoke and the air gate which is connected therewith. While the ears 46 and the connecting portion 49 are 5 illustrated in the drawings as integral with the burner frame they may, however, be formed in any other desired manner, as will be readily understood.

Oil is supplied to the interior of the inverted cup-shaped body of the atomizer by oil supplying means comprising a suitable supply pipe 50 through which oil is supplied generally in a relatively uniform manner or else according to the load requirements, to and through an up-standing pipe 51 into the interior of the inverted cup-shaped body of the atomizer 27. As the vertical shaft 25 rotates the atomizer about its vertically extending axis, the oil delivered into the annular oil receiving space 32 flows upward- 20 ly on the inner face of the inclined peripheral wall 38 of the atomizer as a film due to centrifugal force to the tubes 29 by which the oil is centrifugally delivered as a spray or in atomized form outwardly along a relatively horizontal 25 plane. It will be clear from the drawings that because of the shape of the fan 28 and the arrangement of the disk or body portion of the fan over but in spaced relation to the oil atomizing and delivering device 27, the air passing 30 through the fan in effect cools the oil atomizing and delivering device and protects the same from the heat of the furnace, viz., from the heat resulting from the combustion of the oil and air supplied by the burner. The upstanding pipe 35 which passes through the open bottom of the inverted cup-shaped body of the atomizer is of a length preferably to extend to the upper portion of the atomizer, as clearly shown in Fig. 3 of the drawings, and its upper discharge end 52 40 is preferably bent laterally for discharging the fuel directly against the peripheral wall of the atomizer.

The lower end of the upstanding pipe 51 is connected with a horizontal bore or passage 53 45 in the burner body by a suitable coupling 54 at the inner end of the passage and the supply pipe is connected by a suitable coupling 55 with the outer end of the passage but the supply pipe may be connected with the upstanding pipe in any 50 other suitable manner, as will be readily understood.

The vertically adjustable air gate 28 may be as illustrated in Fig. 3 of the drawings, provided with an adapter ring 56 suitably supported on 55 and carried by the cylindrical body portion of the air gate in a manner permitting its removal and replacement when desired. The adapter ring which is arranged horizontally, is provided at its lower face with a peripheral recess 57 forming a shoulder which fits within the cylindrical air gate and interlocks the adapter ring with the air gate against horizontal or lateral movement. This will enable the adapter ring to fit firmly in proper position on the air gate without danger 60 of accidental displacement in any vertical adjustment of the said air gate. The adapter ring forms a horizontal inwardly extending annular flange at the top of the vertically adjustable air gate and it is of a width to extend from the air 65 gate to the outer ends of the blades of the fan and it is vertically adjustable with respect to the blades of the fan through the vertical movement of the air gate.

The burner frame and the air gate are con- 75

- structed of a standard size and the adapter ring is adapted to be constructed with its inner periphery and the opening formed by the same of different diameters to accommodate burner head assemblies of different sizes. The burner head assembly comprises the fan and the atomizer and if during the life of the burner the boiler or furnace in which the same are used should have to be replaced by a larger one a new head assembly to fit in the new heating plant may be installed at a trifling cost due to the removable adapter ring which adapts burner head assemblies of different sizes for use in connection with the burner frame and air gate of a standard size.
- The adapter ring is provided at its inner periphery with an upstanding annular flange 58 which increases the vertical dimension of the air gate and when the adapter ring is removed the air gate is adapted for use with a fan of increased size. By means of various adapter rings, fans of the required capacity may be used on any oil burner having a standard burner frame and a standard motor and air gate. The oil burner may be installed in connection with a heating apparatus as typified, for example, in Fig. 4.

From said Fig. 4, it will be noted that a rotary oil burner broadly designated as B is installed in association with a horizontally extending hearth H at the center of the hearth whereby atomized oil and air can pass outwardly over the hearth toward and in engagement with a marginal refractory structure S, such as is shown, described and claimed in the aforesaid application. With the normal operation of the rotary burner there results a fuel and flame stream of spiral formation designated by F. The products of combustion pass from the combustion chamber of the heater to the chimney flue in the usual way. The hearth construction and the manner in which the fuel is burned are fully described in the aforesaid companion application.

A salient feature of the invention resides in the interchangeable head assemblies to vary the diameter of the fan and also the diameter of the atomizer. By means of the interchangeable head assemblies atomizers with tube lengths corresponding proportionately to fan diameter may be employed. This is a great advantage as it will enable a small boiler or heater to be equipped with a small fan with properly proportioned atomizer tubes and a greater travel of the air and oil vapor over a heated hearth is thereby obtained than is possible were a fan of greater diameter and longer atomizer tubes used. Atomization depends upon peripheral speed at the tube discharge. By the present invention atomization is balanced with air velocity used in different sizes of fans.

What is claimed is:—

- An oil burner comprising a substantially vertical cylindrical burner frame, a motor actuated upstanding vertical shaft passing through the burner frame, an oil atomizer mounted on the upper end of and rotating with the said shaft, a fan also carried by the said shaft and provided at its periphery with fan blades located adjacent the upper edge of the burner frame, a vertically movable air gate for controlling the volume of air delivered by the fan and consisting of a cylindrical member associated with the upper portion of the burner frame and provided with inclined guiding means arranged to cause an upward or downward movement of the air gate

when the latter is partially rotated, an operating member connected with the air gate for partially rotating the same, and stops located at opposite sides of the operating member and adjustable for positioning the air gate.

2. An oil burner comprising a substantially vertical cylindrical burner frame, a motor actuated upstanding vertical shaft passing through the burner frame, an oil atomizer mounted on the upper end of and rotating with the said shaft, a fan also carried by the said shaft and provided at its periphery with fan blades located adjacent the upper edge of the burner frame, a vertically movable air gate consisting of a cylindrical member associated with the upper portion of the burner frame and provided with inclined guiding means arranged to cause an upward or downward movement of the air gate when the latter is partially rotated, an operating member connected with the air gate for partially rotating the same, and stop screws located at opposite sides of the operating member of the air gate for positioning the latter.

3. An oil burner comprising a substantially vertical cylindrical burner frame, a motor actuated upstanding vertical shaft passing through the burner frame, an oil atomizer mounted on the upper end of and rotating with the said shaft, a fan also carried by the said shaft and provided at its periphery with fan blades located adjacent the upper edge of the burner frame, a vertically movable air gate for controlling the volume of air delivered by the fan and consisting of a cylindrical member associated with the upper portion of the burner frame and provided with inclined guiding means arranged to cause an upward or downward movement of the air gate when the latter is partially rotated, a yoke pivotally connected with the air gate at opposite sides thereof and having an operating arm for partially rotating the air gate, and stops located at opposite sides of the operating arm and adjustable for positioning the same and the air gate.

4. An oil burner comprising a substantially vertical cylindrical burner frame, a motor actuated upstanding vertical shaft passing through the burner frame, an oil atomizer mounted on the upper end of and rotating with the said shaft, a fan also carried by the said shaft and provided at its periphery with fan blades located adjacent the upper edge of the burner frame, a vertically movable air gate for controlling the volume of air delivered by the fan and consisting of a cylindrical member associated with the upper portion of the burner frame and provided with inclined guiding means arranged to cause an upward or downward movement of the air gate when the latter is partially rotated, a yoke pivotally connected with the air gate at opposite sides thereof and having an operating arm for partially rotating the air gate, spaced screw supporting portions rigid with the burner frame and having a connecting portion located beneath the operating arm of the yoke, said screw supporting portions being located at opposite sides of the said operating arm and having threaded openings, and adjusting screws mounted in the threaded openings and arranged to engage the operating arm of the yoke for holding the air gate in adjusted positions.

5. An oil burner comprising a burner frame, a motor secured to and depending from the burner frame and having an upstanding shaft, a fan mounted on the shaft of the motor above the burner frame and having air delivery blades, a

- vertically adjustable air gate associated with the burner frame, a removable adapter ring seated on the air gate and surrounding the fan blades and carried by the air gate in the vertical adjustment thereof for controlling the volume of air delivered by the fan, and means located above the burner frame for discharging oil spray in substantial parallelism with the air discharged by the fan.
6. An oil burner comprising a burner frame, a motor secured to and depending from the burner frame and having an upstanding shaft, a fan mounted on the shaft of the motor above the burner frame and having air delivery blades, a vertically adjustable air gate associated with the burner frame, an adapter ring removably seated upon the air gate and having an upper portion of a different diameter from its lower portion surrounding the fan blades, said adapter ring being carried by the air gate in the vertical adjustment thereof for controlling the volume of air delivered by the fan, and means located above the burner frame for discharging oil spray in substantial parallelism with the air discharged by the fan.
7. An oil burner comprising a burner frame, a motor secured to and depending from the burner frame and having an upstanding shaft, a fan mounted on the shaft of the motor above the burner frame and having air delivery blades, a vertically adjustable air gate associated with the burner frame, an adapter ring removably seated upon the air gate and composed of upper and lower vertical portions and an intermediate approximately horizontal connecting portion, the upper portion of the adapter ring being of a different diameter from the lower portion and surrounding the fan blades for controlling the volume of air delivered by the fan, and means located above the burner frame for discharging oil spray in substantial parallelism with the air discharged by the fan.
8. An oil burner comprising a burner frame, a vertically arranged electric motor located below the burner frame and having an upstanding vertical shaft extending through the burner frame,
- an oil atomizer mounted on the upper end of the vertical shaft, a fan also carried by the vertical shaft and positioned adjacent the oil atomizer and having fan blades located adjacent the upper edge of the burner frame and arranged for centrifugally delivering air outwardly from said fan, a vertically adjustable air gate associated with the burner frame for controlling the volume of air delivered by the fan, and an adapter ring removably seated upon the upper edge of the air gate and forming an extension of the same and located at the delivery ends of the fan blades and surrounding the same.
9. An oil burner comprising a burner frame provided with air inlet openings and having an upstanding annular throat section, an air gate vertically adjustable with respect to the throat section, a motor located below the burner frame and provided with a vertically extending shaft passing through the burner frame, an oil atomizer carried by the upper end of the shaft and including outwardly extending oil delivery pipes, and a fan mounted on the shaft and positioned adjacent the oil atomizer and having a body portion provided with depending fan blades located within an area defined by the body portion of the fan and adjacent the upper edge of the throat section, said fan blades and air gate being of such size relative to each other that the vertical adjustment of the air gate effects an embracing relation of the gate with the fan blades to regulate the volume of air delivered from the fan.
10. An oil burner comprising a frame, a rotat- ing shaft upstanding in the frame, an oil atom- 35 izer mounted on the shaft above the frame in- cluding outstanding atomizing tubes, a fan also mounted on the shaft and positioned adjacent the oil atomizer, said fan including a body plate above said atomizing tubes and blades depending from said plate for centrifugally delivering air 40 outwardly above the frame, and means slideable in the frame and shiftable into, and out of, embrac- 45 ing relation with said fan blades for adjust- ably controlling the volume of air delivered out- wardly from the fan.

THEOPHILUS H. SMOOT.
